DESIGN FOR A CLOSURE CAP

Willis M. Rose, Montclair, N. J., assignor to The Sun Tube Corporation, Hillside, N. J., a corporation of New Jersey

Application August 22, 1935, Serial No. 58,241

Term of patent 14 years

To all whom it may concern:

Be it known that I, Willis M. Rose, a citizen of the United States, residing at Montclair, in the county of Essex and State of New Jersey, have invented a new, original, and ornamental Design for a Closure Cap, of which the following is a specification, reference being had to the accompanying drawing, forming a part thereof.

Figure 1 is a top view of a closure cap embodying my new design.

Figure 2 is a side view of such a cap.

Figure 3 is a bottom view of my new cap design.

The characteristic feature of the design is a cap of the configuration shown, having a flat rim portion at the outer edge of the top, a circular bead of rounded, substantially semi-circular cross-section inside of said rim and a slightly domed center portion within said bead below the top of the bead.

I claim:

The ornamental design for a closure cap, as shown and described.

WILLIS M. ROSE.
